TAPE FOR SLIDE FASTENERS

John E. Fite, Jr., Philadelphia, Pa.

Application February 29, 1944, Serial No. 524,500

8 Claims. (Cl. 139—384)

This invention relates to slide fasteners, and more particularly to the textile tapes employed as the foundations thereof.

A slide fastener normally includes a pair of parallel foundation tapes. These tapes are composed of textile fabric and one edge of each of the parallel strips is thickened, and thereby reinforced. Usually this reinforcement consists of a cord laid on each of the opposite faces of the tape, and sewn thereto by a row of stitches passing through the two cords and the tape fabric, immediately adjacent and paralleling the one edge thereof.

Around the reinforced edges of the tapes are pinched, or otherwise set, the interlocking hook-and-keeper elements of the fasteners, which are commonly referred to in the trade as "scoops." These scoops are composed of metal, plastic or other suitable material and are secured to the edges of the tapes in predetermined spaced relation to each other therealong.

The parallel foundation tapes are normally disposed in a common plane, with the reinforced scoop-bearing edges of the two tapes in close laterally adjacent relation to each other and with the scoops of the respective tapes in alternating interlocking relation.

Each fastener also includes a metal, plastic or other slide, which is employed for engaging and disengaging the scoops. This slide is mounted in a manner to ride on the interlocked scoops, with a minimum amount of rubbing action on the tapes adjacent the inner ends of the scoops.

It has been common practice heretofore to form the foundation tapes of yarns composed exclusively of combed cotton fibres, and to make the tape fabric of one or two ply thicknesses. Normally the widths of these tapes range from $\frac{1}{8}$ of an inch to $1\frac{1}{2}$ inches. The tapes are woven with various numbers of picks of the filling or weft threads per inch, warpwise of the tape fabric, and various numbers of warp ends per inch, weftwise of the tape fabric, in accordance with the size and quality of the yarns employed, in order to provide a sufficient degree of firmness in the tape for supporting the scoops in proper position to enter the guide tracks in the slide; to provide a high degree of tensile strength in the tape; and to give the tapes satisfactory wearing qualities for enduring the hard usage to which the slide fasteners are frequently subjected.

In many instances, manufacturers of slide fasteners have encountered considerable difficulty with the tapes composed of the combed cotton

fibres, in that the tapes tend to wrinkle or undulate and become unsightly along the scoop-bearing edges thereof. The undulations in the tapes interfere with the smooth normal functioning of the slide in effecting engagement and disengagement of the scoops.

Analysis indicates that the unsightly troublesome wavy conditions which develop in slide fasteners in the course of use arises from a longitudinal shrinking of the foundation tapes. This shrinkage causes the scoops to be drawn into more closely spaced relation to each other, and the resultant reduction in the spacing of the scoops requires the expenditure of greater effort in order to effect the interlocking action of the scoops, by the slide. This causes the slide to work with a jerky action.

The reduction in the spacing of the scoops, together with the pressure exerted on the edge 20 of the tape as a result of the scoops being pinched around the reinforced corded edge of the tape, restricts the shrinkage of the scoop-bearing edge of the tape, while throughout the remainder of 25 its width, the tape is unrestricted and free to shrink in all directions. Consequently, a shrinkage differential is set up between the scoop-bearing edge of the tape and the remainder of the width of the tape fabric.

The shrinkage differential between the immediately adjacent portions of the tape develops 30 an internal force in the free portion of the tape adjacent the restricted reinforced edge portion of the tape, which reacts perpendicularly to the normal plane of the tape in the reinforced edge portion thereof, under the contractive force of 35 shrinkage lengthwise of the tape. This condition results in the scoop-bearing edge of the tape being forced out of the normal plane of the tape into a series of undulations along the length of 40 the tape.

The primary object of the present invention is to produce a tape for use as the foundation of a slide fastener which will remain flat at all times. The construction of the tape forming the 45 subject matter of the present invention will be fully disclosed hereinafter, reference being had to the accompanying drawing, of which:

Figs. 1 and 2 diagrammatically illustrate, on a greatly enlarged scale, a face view and typical 50 transverse sectional view respectively of a slide fastener employing foundation tapes made in accordance with the present invention.

Primarily the invention resides in the proper selection of material for the production of the tape. To this end, the material best suited for

the purpose of the present invention, and which has proven to meet all the requirements, is high tenacity synthetic filament, including rayon or nylon, of $1\frac{1}{4}$ denier (approximately 3,952,704 yards per pound), or finer, reduced to staple lengths of not less than $1\frac{1}{8}$ inches and spun into yarn of two or three ply twist.

Of equal importance is the particular weave employed. To this end, a conventional four leaf twill weave has proven to be best suited to the purpose of the invention.

The tape of the present invention is woven, for example, in five standard widths, namely, $\frac{3}{8}$ ", $\frac{1}{2}$ ", $\frac{5}{8}$ ", $\frac{3}{4}$ " and 1".

The thickness of the tape, is also of importance and in all instances, regardless of width, the tape is confined to a thickness not less than .010" or greater than .028".

The number of picks of filling per inch, throughout the length of the tape, and the number of warp ends per inch, throughout the width of the tape, may be substantially equal, or may vary relatively in the tapes of different widths.

In the present instance it is preferable to employ the maximum number of warp ends which can be conveniently handled in the weaving process within the width of the particular fabric being woven, thus the number of warp ends per inch of the width of the tape may vary in the tapes of different standard widths.

Using the maximum number of warp ends in a given width of tape and a substantially corresponding number of filling or weft threads in each unit of the length which is equal to the width of particular strip being fabricated, under the four leaf twill weave, provides a tape of maximum texture having a maximum amount of flexibility or flaccidity over the entire area of the strip, and affords a maximum amount of planar yieldability in the plane of the tape, particularly in that portion of the tape lying between the inner side of the corded edge reinforcement located adjacent the one edge of the tape fabric and the opposite free edge of the tape fabric.

The following table is provided to illustrate relative differences in the tapes of different widths.

	Width, inches					
	$\frac{3}{8}$	$\frac{1}{2}$	$\frac{5}{8}$	$\frac{3}{4}$	$\frac{3}{4}$ heavy	1
Warp-B. S. ....pounds..	40	60	80	100	110	120
Warp-B. S. ....do....	60	110	150	150	200	150
Thickness.....inches.	0.10	.019	.019	.019	.025	.019
Number of warp ends....	48	48	60	84	59	112
Number of wefts per inch..	64	56	56	56	142	56

¹ Double.

In the accompanying drawing, the foundation tapes are designated as A1 and A2 respectively. Each tape is thickened along one edge, as indicated at a, a.

The scoops b, b are of usual construction and are pinched or otherwise set to grip the thickened edges a, a of the tapes firmly at relatively spaced points longitudinally of the tapes. The slide B, likewise, is of usual construction and cooperates with the scoops b, b to effect engagement and disengagement thereof, in the usual manner.

The conventional four leaf twill weave produces in the fabric four parallel longitudinal areas a1, a2, a3 and a4 respectively, in a herring-bone pattern, with the lines of the pattern in laterally adjacent successive areas disposed at relatively sharp angles with respect to each other. This

arrangement affords considerable relative movement between the adjacent longitudinal areas a1, a2, a3 and a4, within the body of the tape, in the plane X—X (Fig. 2) of the tape fabric, longitudinally of the tapes, and this construction, functioning in this manner, permits the tapes to give and take longitudinally with any shrinkage or stretching of the fabric of any article to which the foundation tapes may be secured.

The material employed, i. e. the spun staple yarns composed of the synthetic filaments having the characteristics previously noted, in conjunction of the four leaf twill weave, provides a condition of flaccidity and yieldability in the tape fabric, in the plane of the fabric, which is not subject to the internal strains which heretofore have been responsible for the undulating of the corded edges of the foundation tapes of the prior art.

In fact, observance of the functioning of fasteners employing the foundation tapes of the present invention appears to indicate that as the slide B is moved along the interlocking scoops b, b to effect progression of the interlocking of the successive disengaged scoops, a small degree of extensibility in the corded edges a, a to which the scoops b, b are secured, takes place. This characteristic facilitates the interlocking of the scoops b, b by the slide B and enables the slide B to be moved with a smooth easy motion along the tapes.

Any shrinkage differential which might be produced in adjacent longitudinal sections of the tape appears to be dissipated within the tape by reason of the relative planar yieldability afforded the adjacent sections of the tape. Thus no undulating of the tapes occur and the tapes retain their flat flaccid condition at all times.

I claim:

1. A foundation tape for slide fasteners, comprising a narrow textile fabric composed of high tenacity synthetic staple of a length not less than $1\frac{1}{8}$ inches and of a weight not in excess of $1\frac{1}{4}$ denier spun into yarns of not less than two or more than three ply twist, with said yarns exclusively constituting the warp and weft of the tape fabric interwoven in a four leaf twill pattern.

2. A foundation tape for slide fasteners, comprising a narrow textile fabric composed of high tenacity synthetic staple of a length not less than $1\frac{1}{8}$ inches and of a weight not in excess of $1\frac{1}{4}$ denier spun into yarns of not less than two or more than three ply twist, with said yarns exclusively constituting the warp and weft of the tape fabric interwoven in a four leaf twill pattern, said fabric having a thickness range between a minimum of .010 inch and a maximum of .028 inch.

3. A foundation tape for slide fasteners, comprising a narrow textile fabric composed of high tenacity synthetic staple of a length not less than $1\frac{1}{8}$ inches and of a weight not in excess of $1\frac{1}{4}$ denier spun into yarns of not less than two or more than three ply twist, with said yarns exclusively constituting the warp and weft of the tape fabric interwoven in a four leaf twill pattern, said tapes being formed in widths of predetermined steps ranging from $\frac{3}{8}$ inch to 1 inch, and said warps having a range of breaking strength between a minimum of 40 lbs. and a maximum of 120 lbs. proportional to said predetermined steps respectively in said width range.

4. A foundation tape for slide fasteners, comprising a narrow textile fabric composed of high

tenacity synthetic staple of a length not less than $1\frac{1}{8}$ inches and of a weight not in excess of $1\frac{1}{4}$ denier spun into yarns of not less than two or more than three ply twist, with said yarns exclusively constituting the warp and weft of the tape fabric interwoven in a four leaf twill pattern, said tapes being formed in widths of predetermined steps ranging from $\frac{3}{8}$ inch to 1 inch, and said wefts having a range of breaking strength from a minimum of 60 lbs. to a maximum of 150 lbs. proportional to said predetermined steps respectively in said width range.

5. A foundation tape for slide fasteners, comprising a narrow textile fabric composed of high tenacity synthetic staple of a length not less than $1\frac{1}{8}$ inches and of a weight not in excess of $1\frac{1}{4}$ denier spun into yarns of not less than two or more than three ply twist, with said yarns exclusively constituting the warp and weft of the tape fabric interwoven in a four leaf twill pattern, said fabric having a thickness range between a minimum of .010 inch and a maximum of .028 inch, said tapes being formed in widths of predetermined steps ranging from $\frac{3}{8}$ inch to 1 inch, and said warps having a range of breaking strength between a minimum of 40 lbs. and a maximum of 120 lbs. proportional to said predetermined steps respectively in said width range.

6. A foundation tape for slide fasteners, comprising a narrow textile fabric composed of high tenacity synthetic staple of a length not less than $1\frac{1}{8}$ inches and of a weight not in excess of $1\frac{1}{4}$ denier spun into yarns of not less than two or more than three ply twist, with said yarns exclusively constituting the warp and weft of the tape fabric interwoven in a four leaf twill pattern, said fabric having a thickness range between a minimum of .010 inch and a maximum of .028 inch, said tapes being formed in widths of predetermined steps ranging from $\frac{3}{8}$ inch to 1 inch, and said wefts having a range of breaking strength from a minimum of 60 lbs. to a maxi-

10 mum of 150 lbs. proportional to said predetermined steps respectively in said width range.

7. A foundation tape for slide fasteners, comprising a narrow textile fabric composed of high tenacity synthetic staple of a length not less than $1\frac{1}{8}$ inches and of a weight not in excess of $1\frac{1}{4}$ denier spun into yarns of not less than two or more than three ply twist, with said yarns exclusively constituting the warp and weft of the tape fabric interwoven in a four leaf twill pattern, said tapes being formed in widths of predetermined steps ranging from $\frac{3}{8}$ inch to 1 inch, said warps having a range of breaking strength between a minimum of 40 lbs. and a maximum of 120 lbs. proportional to said predetermined steps respectively in said width range, and said wefts having a range of breaking strength from a minimum of 60 lbs. to a maximum of 150 lbs. proportional to said predetermined steps respectively in said width range.

15 8. A foundation tape for slide fasteners, comprising a narrow textile fabric composed of high tenacity synthetic staple of a length not less than $1\frac{1}{8}$ inches and a weight not in excess of $1\frac{1}{4}$ denier spun into yarns of not less than two or more than three ply twist, with said yarns exclusively constituting the warp and weft of the tape fabric interwoven in a four leaf twill pattern, said fabric having a thickness range between a minimum of .010 inch and a maximum of .028 inch, said tapes being formed in widths of predetermined steps ranging from $\frac{3}{8}$ inch to 1 inch, said warps having a range of breaking strength between a minimum of 40 lbs. and a maximum of 120 lbs. proportional to said predetermined steps respectively in said width range, and said wefts having a range of breaking strength from a minimum of 60 lbs. to a maximum of 150 lbs. proportional to said predetermined steps respectively in said width range.
